Michael. Grogan.

UNITED STATES PATENT OFFICE.

MICHAEL GROGAN, OF SAVANNAH, GEORGIA.

LUBRICATOR FOR SAW BLADES.

Application filed April 24, 1925. Serial No. 25,703.

To all whom it may concern:

Be it known that I, MICHAEL GROGAN, a citizen of the United States, residing at Savannah, in the county of Chatham and State of Georgia, have invented certain new and useful Improvements in Lubricators for Saw Blades, of which the following is a specification.

The present invention relates to a lubricating device for saws, and aims to provide a novel and improved device of that character for conveniently and efficiently supplying oil to the sides of a saw blade while the same is in use to prevent friction between the blade and the opposite sides of the cut, thus enabling the saw to render better and longer service.

Another object of the invention is to provide a lubricating device which can be readily attached to saws now on the market without marring the appearance or interfering with the use thereof, said device also being readily removable from the saw for permitting cleaning or repairing thereof.

A further object of the invention resides in the provision of such an oiling device for saws, whereby the flow of oil from the oil reservoirs to the opposite sides of the saw blade is at all times under direct control of the operator for permitting the desired amount of oil to flow to said blade.

It is also an object of the invention to provide a lubricator of the kind indicated, which is simple and substantial in construction, which can be manufactured economically, and which will be thoroughly efficient and practical in use.

With the foregoing and other objects in view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein:

Figure 1 is a fragmentary side elevation of a saw showing my improved device applied thereto,

Figure 2 is a plan view thereof,

Figure 3 is a section taken on line 3—3 of Figure 1,

Figure 4 is a vertical section taken on line 4—4 of Figure 2, and

Figure 5 is also a vertical section taken on line 5—5 of Figure 2.

In carrying out the invention, the numeral 10 designates a saw blade having a handle 11 attached thereto, said handle having removably attached to the same and on each side thereof a drum shaped oil reservoir 12, each of which are identical in size and shape. The oil reservoirs are permanently attached together by a cross plate 13 extending across the handle 11 of the saw and being secured thereto by screws 14. On the outer cylindrical surfaces of each drum is provided a U-shaped member 15 for receiving the opposite ends of a plate 16 extending across the handle in a manner similar to the member 13 and being secured to said handle by screws 17, said plate 16 providing detachable supporting means for the forward portions of the drums.

Arranged in each of the drum shaped reservoirs 12 and extending at an angle therein is a tapered tube 18, said tubes extending through openings 19 in the upper cylindrical wall of the drums, and having their lower ends 20 screw-threaded in bosses 21 constructed on the interior of the drums. An opening 22 is arranged in each of said tubes 18 below the level of oil in the reservoirs to permit oil to enter into said tubes, the entrance of which is controlled by sliding valves 23, stems 23', and tapered portions 24, said tapered portions 24 being arranged to engage the interior tapered wall of the tubes. The valve stems 23' extend upwardly through packing members 25 positioned in the upper ends of the tubes 18, and have their upper extremities connected together by a cross rod 26, which extends through openings 27 arranged in the valve stems 23', said cross rod having a head 28 on one end and a nut 29 on the other to permit the same to be removed from the valve stems in order to permit disassembling of the device.

The upper ends of the tubes 18 have screw threaded heads 30 thereon for threadedly receiving cap members 31 having inwardly directed annular flanges thereon for engaging the packing members 25, which are cone shape, to force the same in tight engagement with the tapered seats 32 arranged in the tubes 18. It can be seen that the packing members as described will prevent leakage of oil out of the upper ends of the tubes 18.

Positioned on the plate 13 and arranged adjacent the space between the tubes 18 is arranged a U-shaped member 33 having a pin 34 extending between its free ends for pivotally supporting a lever 35, which has an opening in one end thereof through which extends the cross rod 26. On the opposite end of said lever which extends to the opposite side of the pivot pin 34 is arranged a thumb engaging portion 36 to be engaged by the operator for swinging said lever on its pivot to unseat the valves 23 and permit oil to enter the tubes 18. A second pin 37 extends between the opposite sides of the U-shaped member 33 for supporting thereon a coil spring 38 having its opposite ends engaging the right portion of the U-shaped member 33 and the lever 35 respectively in order to yieldably hold said lever in a position with the opening 22 in the tube 18 closed.

Attached to the outer cylindrical wall of each of the drums 12 is the opposite ends of a U-shaped pipe 39 having a branch portion 40 communicating therewith intermediate its ends. The branch portion 40 has arranged thereon a threaded cap 41 for closing the same while the saw is in use, said cap being removed when it is desired to supply a quantity of oil to the drums or oil reservoirs 12.

Arranged upon the lower portions of the drums 12 are screw threaded bosses 42, each having attached thereto an elbow pipe 43, said elbow pipes being arranged to extend towards each other and adjacent the opposite sides of the saw blade 10, as illustrated by the numeral 44. Arranged about the portions 44 of the elbows 43 are U-shaped brackets 45, which have their opposite ends attached to the handle 11 in order to hold said elbows in a rigid manner. The elbows 43 are arranged to communicate with the interior of the tubes 18 so as to receive oil from said tubes to supply the same to the saw blade, said supply being regulated by a pair of nuts, one arranged upon each of said elbows for engaging the sides of the blade. It can be seen that by revolving the nuts on the portions 44 of the elbows 43, said nuts will be either moved towards or away from the blade, thus regulating the flow of oil to the saw blade.

Positioned about the valve stems 23' are coil springs 47, each having one end thereof attached to said stems 23' as at 48, while the opposite ends of said springs extend through apertures 49 arranged in the tapered tubes 18, and have received thereover collars 50 arranged about the tubes 18 in order to secure said ends of the springs to the tubes 18 in a rigid manner. By attaching one end of the springs 47 to the valve stems 23' and the opposite ends of the springs to the tubes 18, it will be noted

that the springs 47 will prevent rotation of the tubes 18, which would tend to disconnect the same from the bosses 21, as each of the valves 23 is held against rotation by the cross pin 26 extending through the upper ends of the stems 23' thereof. When removing the tubes 18 for cleaning or the like, it is necessary to rotate said tubes against tension of the springs 47 unless the cross pin 26 has been removed prior to such rotation.

It will be noted that the opening 19 in each of the drums 12 is of sufficient size to permit the entire assembly carried by said tubes to be removed therethrough as an entirety.

As to the operation of my improved device, the filling cap 41 is removed from the branch pipe 40 and oil supplied to the cylindrical drums by pouring the same into said branch 40. After the cap 41 has been replaced and the saw is brought into operation, the thumb engaging portion 36 of the lever 35 may be depressed in order to supply oil to the opposite sides of the blade 10, the operation of the lever 35 causing the valves 23 to be raised against tension of the spring 38 in order to unseat the tapered portions 24 carried by said valves which will permit oil to flow freely into the tubes 18 and elbows 43, from which the same is deposited on the blade. As it is necessary to operate the lever 35 in order to supply oil to the blade of the saw, it can be seen that the flow of oil to the blade is at all times under direct control of the operator for permitting the desired amount thereof to be supplied to said blade.

Having thus described my invention, what I claim as new is:

1. A lubricating device for saws comprising a pair of oil reservoirs one attached on each side of said saw, tubes communicating with said reservoirs for supplying oil to the blade of the saw, valves for regulating the flow of oil from said reservoir to said tubes, a rod connecting said valves together to cause the same to operate simultaneously, and means engaging said rod for operating said valves.

2. A lubricating device for saws comprising a pair of oil reservoirs one attached on each side of said saw, a tube extending through each of said reservoirs, means attached to said reservoirs and communicating with said tubes for supplying oil to the opposite sides of a saw blade, each of said tubes having an aperture in the side wall thereof for permitting the interior of said reservoirs to communicate with the interior of said tubes, a sliding valve arranged in each of said tubes for opening or closing communication between said reservoirs and tubes, a cross rod detachably connected to each of said valves for causing the same to

operate simultaneously, a lug carried by said reservoirs, a lever pivotally connected to said lug and having one end thereof connected to said cross rod for opening and closing said valves, a U-shaped oil supplying pipe having its opposite ends in communication with said reservoirs, and a branch pipe attached to said U-shaped pipe intermediate its ends for receiving the oil 10 to be supplied to said reservoirs.

3. A lubricating device for saws, comprising a pair of oil reservoirs one attached to each side of said saw, a pair of elbow pipes attached to said reservoirs and having communication therewith, said elbow pipes being arranged on the opposite sides 15 of the saw blades and having portions thereof extending towards each other and adjacent said saw blade, and members carried 20 by said elbows adjustable towards or away from said saw blade for regulating the flow of oil from the elbow pipes to the blade.

4. A lubricating device for saws, comprising a pair of oil reservoirs one attached to each side of the saw, a pair of elbow pipes one attached to each of said reservoirs and being in communication therewith, said elbows being arranged upon the opposite sides 25 of the saw blade and extending towards and

adjacent said blade, and members threaded 30 on said elbow pipes as to be adjustable towards or away from the blade for regulating the flow of oil from the elbows to the blade.

5. A lubricating device for saws, comprising a pair of oil reservoirs one arranged upon each side of the saw, a pair of tapered tubes one arranged in each of said reservoirs and having one end thereof threadedly attached to the reservoir, means attached to 40 said reservoirs and communicating with the threaded ends of said tubes for supplying oil to the blade of a saw, said tubes having apertures in the side walls thereof, a sliding valve arranged in each of said tubes 45 for opening or closing communication through the apertures in said tubes, spring means attached to said valves and said tubes for yieldably holding one against rotation with relation to the other, a rod connecting 50 the upper ends of said valves together to cause the same to operate simultaneously and to also hold said valves against rotation, and a hand lever attached to said rod for operating said valves. 55

In testimony whereof, I have affixed my signature.

MICHAEL GROGAN.
